UNITED STATES PATENT OFFICE.

ALFRED T. WARREN, OF NEW YORK, N. Y.

KEYLESS LOCK.

Application filed February 20, 1926. Serial No. 89,688.

This invention pertains to locks and has particular reference to a keyless lock which is particularly, although not necessarily, designed as a lock for trunks.

5 Primarily the invention comprehends a strong, durable, efficient and readily operable lock which dispenses with the necessity of a key and eliminates the trouble or inconvenience connected with key-actuated locks.

10 More specifically the invention comprehends a keyless lock including a bolt, and means for releasing the bolt consisting of a trip for moving the bolt to released position, an actuator adapted to engage with and move the trip to effect the release of the bolt, and an improved means for necessitating the rotation of said actuator predetermined distances in opposite directions from a given starting point to reach the 15 point of operative engagement with the trip.

The invention furthermore contemplates a keyless lock including a bolt-releasing mechanism which is subject to a practically unlimited variation of the combination of movements, to effect the release of the bolt, thereby insuring the users against duplication of the combination movements.

15 The invention as a further object aims to provide a manipulating means which practically eliminates the possibility of breakage especially when the device is adapted as a lock for trunks which are obviously subjected to rough usage.

20 With the above recited and other objects in view, reference is had to the following specification and accompanying drawings in which there is exhibited one example or embodiment of the invention which is in no way intended as a limitation upon the scope 25 of the appended claims as it is to be clearly understood that variations and modifications which properly fall within the scope of said claims may be resorted to when found expedient.

25 In the drawings—

Figure 1 is a front view of the lock in locked condition;

Fig. 2 is a sectional view taken approximately on the line 2—2 of Fig. 1;

Fig. 3 is a sectional view taken approximately on the line 3—3 of Fig. 1;

Fig. 4 is a rear view of the lock with the cover plate removed;

Fig. 5 is a similar view therethrough taken approximately on the line 5—5 of Fig. 4;

Fig. 6 is a rear view of the lock with the actuator plate removed and illustrating the actuator element in the initial starting point position engaging the stop;

Fig. 7 is a similar view illustrating the actuator element during its passage through one of the passageways;

Fig. 8 is a similar view with parts in section and illustrating the actuator element 65 engaging the trip lock and retracting the bolts;

Fig. 9 is an inner face view of the rear cover plate;

Fig. 10 is a perspective view on the manipulating element removed from the lock.

Referring to the drawings by characters of reference, the lock, designated generally by A, is carried by the free end of a hasp B, pivotally attached, as at C, to a base D, 75 secured to the trunk body E. The lock A is of substantially cylindrical formation and is designed to be received in a keeper F on the trunk cover or lid G.

The lock A consists of a body 10, which is formed with circular concentric recesses 11 and 12 in its opposite faces, joined by a concentric axial bore 13. The body 10 is further provided with one or more radial inwardly extending bores 14 in its periphery, in each of which a bolt 15 is mounted for sliding movement, and between the inner ends of which bolts and the inner ends of the bores 14, coiled expansion springs 16 are interposed for normally projecting the bolts outwardly to engage behind the inner peripheral rim 17 of the keeper F. As customary in spring locks of this type, the outer ends of the bolts 15 are formed with inclined faces 18 to effect the initial camming of the bolts when the lock body is swung into the keeper so that the locking action is automatic. Each bolt is provided with a pin 19 which projects through a slot 20 in the body extending longitudinally of the bore 14 and establishing communication with the recess 11 so that the free end of the pin projects into the recess. The lock will hereinafter be described as one provided with a pair of bolts 15, although it is to be understood that one or more bolts may be employed without affecting the scope of the invention.

105 A lever 21 is fulcrumed at 22 on the inner wall of the recess 11 and one arm 23 of the lever engages the outer face of the pin 19 of the bolt 15 so that radial outward swinging movement of the opposite arm 24 of the

lever will effect a retraction of the bolt. A similar lever 25 is fulcrumed at 26 to the inner wall of the recess 11, and has its arm 27 engaging the outer face of the pin 19 of the opposite bolt. The remaining arm 28 overlaps the arm 24 of the lever 21 so that movement imparted to the lever 21 to retract the first-mentioned bolt will simultaneously effect the movement of the lever 25

10 and retraction of the opposite bolt.

In order to provide means for swinging the arm 24 radially outward to effect retraction of the bolts, an actuator pin 30 is provided, which pin is carried by an actuator plate 31 rotatably mounted in the recess 11 on the squared reduced end 32 of the shank 33 of a manipulating disk 34. The manipulating disk is arranged in the outer recess 12 with its shank 33 extending through the axial bore 13 and with the squared end projecting into the recess 11. The actuator disk is maintained in place on the squared end 32 by a nut 35 threaded on the threaded reduced extremity 36 of the squared end 32.

15 The actuator pin is mounted in a radial slot 37 in the plate 31 and is normally urged radially outward by suitable means, such as a spring 38. In order to guide the actuator pin 30 in its movements and to guide the initiated operator in bringing the actuator pin into operative engagement with a trip lug 39 formed on the lever arm 24, a concentric spaced series of substantially circular walls 40, 41, 42 and 43 are formed on and 20 project rearwardly from the inner end wall of the recess 11, which walls define, respectively, therebetween guide grooves 44, 45 and 46. The lug 39 is formed with a cam face 47 and with a substantially radially disposed end face 48, the face 47 completely 25 intersecting the outermost guide groove 44 and partially intersecting the intermediate guide groove 45 at a tangent and the face 48 intersecting the outer and intermediate 30 grooves 44 and 45 at substantially a right angle for a purpose which will hereinafter appear.

The wall 42 is formed with passageways 49 and 50 establishing communication between the guide grooves 45 and 46, the wall 41 being formed with passageways 51, 52 and 53 establishing communication between the guide grooves 45 and 44. The passageway 49 is normally closed by an outwardly 35 opening closure 54 which is in the nature of a spring tongue normally adapted to swing inwardly to a closed position. The passageway 51 is normally closed by an outwardly opening closure 55 in the nature of a spring tongue normally tending to spring to an inwardly closed position. An arcuate spring element 56 is connected to the wall 42 and normally extends radially outward at an angle from the passageway 50 in the 40 wall 42 through the passageway 53 in the

5 wall 41 and into engagement with the inner periphery of the outer wall 40. The outer wall 40 is provided with a slot or recess 57, through which the terminal of an arm 58 slightly protrudes, said arm 58 being divided 59 and provided with an integral second arm 60 lying outside of the outer wall 40, the purpose of which will hereinafter appear.

In order to provide a definite starting point from which the actuator pin starts when manipulating the lock, a stop element 61 is provided in the inner groove 46, said stop element being preferably in the nature of a screw which is threaded into one of 80 a series of threaded openings 62 in the inner wall of the innermost groove 46, this screw 61 being selectively arranged in the series of threaded openings 62 for the purpose of varying the combination of movements necessary to bring the actuator pin to its destination where it will operatively engage the cam face 47 at its point of intersection with the outer groove 44.

The rear recess 11 is enclosed by a cover 90 plate 63 which in addition to concealing and protecting the elements within the recess, is formed with a circumferentially spaced series of notches or teeth 64 with which the knob 65 of a spring arm 66 is adapted to 95 coact. The arm 66 is secured to the actuator disk 31 so that the operator in manipulating the lock may gage either by the sense of hearing or touch, the degrees of turning movement of the actuator pin from the starting point where it is in engagement with the stop element 61.

In use and operation when the lock is in a locked condition, the initiated operator will first, in accordance with the combination of movements, turn the manipulating disk 34 to the left, said manipulating disk being provided with finger-receiving recesses 67 for the purpose of facilitating the turning thereof. The turning movement to the left 105 is continued until the actuator pin engages the stop 61 which the initiated operator will know to be the definite starting point and which stop will necessarily be engaged by the actuator pin irrespective of its position, 110 providing the knob is turned to the left. From this position the operator will turn the manipulating disk 34 to the right, predetermined distances gaged by the number of its teeth which the knob 65 will indicate, 115 so that the actuator pin is brought into alignment with the free end of the closure tongue 54 of the passageway 49. At this point the spring 38 being of a greater tension than the spring tongue closure 54, will 120 open the closure 54 radially outward and enter the guide groove 45. The initiated operator then turns the manipulating disk to the left the predetermined number of notches which will dispose the actuator pin 125

130

30 in alinement with the passageway 51. The operator then turns the manipulating disk in the opposite direction to the right the required number of notches to cause the actuator pin under the tension of the spring 38, to swing the closure tongue 55 radially outward so that said actuator pin passes through the passageway 51 into the outermost groove 44. A reverse turning movement of the manipulating disk 34 to the left the required number of notches will obviously bring the actuator pin into operative engagement with the cam face 47 of the trip lug 39 so that the lever arms 24 and 28 will simultaneously swing outwardly to effect the retraction of the bolts 15.

From the foregoing it is obvious that an uninitiated operator in attempting to manipulate the lock to open the same, will be confronted with many difficulties: (1) Presuming the actuator pin is in the position illustrated in Fig. 6, if he turns the manipulator disk too far so that the actuator pin after passing through the passageway 49 registers with the passageway 52, the said actuator pin will be forced into the outermost groove 44; and (2) if he continues to turn to the right the pin will flex and pass the arcuate closure element 56 and abut the right-angular face 48 of the trip lug. If he turns in a reverse direction after meeting this difficulty, the arcuate element 56 will guide the actuator element back into the inner groove 46. Presuming the operator should after manipulating the lock to bring the actuator pin into the outer groove 44 through the passageway 52, attempt to turn to the left, the actuator pin riding under the influence of the spring 38 on the inner periphery of the outer wall 40 will engage the terminal of the arms 58 which would be swung to the dotted-line position and prevent a further movement in this direction. It is further obvious that in event the uninitiated operator gets the actuator pin in the groove 45 and turns too far to the left so that the pin is brought into contact with that portion of the cam face 47 which extends into the groove 44, the arms would be partially moved outwardly until the pin passed beyond the end face 48 which would prevent turning movement of the same to the right and of necessity the pin would have to be moved outwardly in the same direction where it would be guided into the end guide groove 46. In event the uninitiated operator should, after properly manipulating the lock, get the actuator pin through the passageway 51 and into the outer groove 44, but should continue to turn to the right beyond the arm 58, proper manipulation of the lock to release the same would be frustrated as the only way in which the actuator pin could be moved again into the outer groove 44, to a proper position to engage the cam face 47,

would be by returning to the center guide groove.

Resetting of the lock after the same has been opened is accomplished by turning the manipulating disk to the left so that the actuator pin 30 rides completely over the cam face 47 and beyond the end face 48 thereby disposing the actuator pin in a position which necessitates the movement of the same to its starting point abutting the stop screw 61.

It is furthermore obvious that the combination of movements essential to the proper manipulation of the lock to open the same, may be varied by changing either the position of the stop screw 61, the position of the passageways 49 and 51, or by inverting the direction of operation by reversing the arrangement of the elements. Under this construction it is obvious that a practically unlimited number of combinations may be employed to prevent duplication. It will further be noted that the manipulating disk 34 has its outer face flush with, or, if desired, slightly within the outer face of the lock body so that possibility of breaking or other damage thereto is reduced to an absolute minimum.

What is claimed is:

1. A keyless lock, including a bolt, and means for moving the same to an unlocked position, comprising a pivoted arm operatively associated with the bolt and having a trip lug formed with a cam face, a concentric series of circular walls defining therebetween guide grooves or channels, the outermost groove or channel being transversely intersected by the trip lug, the intermediate walls having circumferentially spaced openings constituting passageways establishing communication between the adjacent grooves, outwardly swingable normally closed gates for said passageways, a pin movable in the grooves and engageable with the cam face of the trip lug when moved in one direction in the outer groove for actuating the trip lug to move the bolt to an unlocked position, means for normally urging the pin radially outward to cause the same to swing the gates outward when moved into engagement with the free ends thereof, whereby to enter the next adjacent outer groove, and a stop element in the inner groove with which the pin engages to constitute a starting point for the operation of the lock.

2. A keyless lock, including a bolt, and means for moving the same to an unlocked position, comprising a pivoted arm operatively associated with the bolt and having a trip lug formed with a cam face, a concentric series of circular walls defining therebetween guide grooves or channels, the outermost groove or channel being transversely intersected by the trip lug, the intermediate walls having circumferentially spaced openings

constituting passageways establishing communication between the adjacent grooves, outwardly swingable normally closed gates for said passageways, a pin movable in the grooves and engageable with the cam face of the trip when moved in one direction in the outer groove for actuating the trip lug to move the bolt to an unlocked position, means for normally urging the pin radially outward to cause the same to swing the gates outward when moved into engagement with the free ends thereof, whereby to enter the next adjacent outer groove, and a circumferentially adjustable stop element in the inner groove with which the pin engages to constitute a starting point for the operation of the lock.

3. A keyless lock including a casing, a spring-pressed bolt normally projected therefrom to a locked position and mechanism for retracting the bolt to an unlocked position comprising a pivoted arm operatively engaging the bolt and having a cam face, a series of concentric annular guide ways the outer one of which is intersected by the cam face of the arm, said guide ways having circumferentially spaced communicating passageways, a circumferentially and radially movable actuator member normally positioned in the inner-most guide way and normally urged outwardly whereby upon proper rotation in opposite directions the same is moved outwardly through the passages to the outermost guide way for engaging the cam face and tripping the arm to retract the bolt.

4. In a lock having a spring-pressed nor-

mally projected bolt, mechanism for retracting the bolt including an arm operatively associated with the bolt, means defining a series of concentric annular guideways, the outer end of which is intersected by said arm, the said guideways having circumferentially spaced communicating passages, and a circumferentially and radially movable actuator element normally positioned in the innermost guideway and normally urged outwardly whereby upon proper rotation in opposite directions the same is moved outwardly through the passages to the outermost guideway for engagement with the arm to effect the retraction of the bolt.

5. In a lock having a spring-pressed normally projected bolt, mechanism for retracting the bolt including an arm operatively associated with the bolt, means defining a series of concentric annular guideways, the outer end of which is intersected by said arm, the said guideways having circumferentially spaced communicating passages, and a circumferentially and radially movable actuator element normally positioned in the innermost guideway and normally urged outwardly whereby upon proper rotation in opposite directions the same is moved outwardly through the passages to the outermost guideway for engagement with the arm to effect the retraction of the bolt, the innermost guideway having a circumferentially adjustable stop element with which the actuator element is engageable to constitute a starting point for the operation of the lock.

ALFRED T. WARREN.
